CLAIM

The ornamental design for a sole structure, as shown and described.

DESCRIPTION

FIG. 1 is a lateral side and bottom view in perspective of a sole structure showing my new design;

FIG. 2 is a medial side and bottom view in perspective thereof;

FIG. 3 is a lateral side view thereof;

FIG. 4 is a medial side view thereof;

FIG. 5 is a top view thereof;

FIG. 6 is a bottom view thereof;

FIG. 7 is a front view thereof; and,

FIG. 8 is a rear view thereof.

The embodiment of FIGS. 1-8 shows a right-footed form of the sole structure. A second embodiment for a left-footed form of the sole structure, which is a mirror image of the right-footed form for each embodiment, is not illustrated. Broken line illustrations in the figures show portions of the sole structure that form no part of the claimed design.
